RAILWAY SIGNAL SYSTEM

Lloyd Espenschied, Hollis, N. Y.

Application August 24, 1926, Serial No. 131,146

7 Claims. (Cl. 246—63)

This invention relates to railway signal and automatic train control systems, and more particularly to the means employed for transmitting the signal indications between the wayside and the train.

In a broad sense, the present invention employs the same fundamental principle as that disclosed in my Patent No. 1,517,549, granted December 2, 1924. The system there described is characterized by the use of an inert wayside circuit and by, (1) the transmission of energizing electric power from the train into the wayside circuit, (2) the transmission of the power back again to the train after having been controlled in accordance with traffic conditions ahead and (3) the actuation of the signal device on the train by the return transmission. The earlier embodiment provided means for discriminating between the outgoing and the return transmission and of thereby insuring that the energy which is effective in operating the signal device is that which has been subjected to wayside control in accordance with traffic conditions.

The system of the present invention differs from that disclosed in the earlier patent in several respects but particularly in the method employed for discriminating between the exciting energy sent into the wayside system and the signaling energy returned to the train. In accordance with the present invention two wayside circuits are set up, one for the outgoing and the other for the return transmission and are so superimposed one upon the other, as to enable the same wayside inductors to be employed for both circuits. Discrimination between these two circuits is accomplished by disposing them in a mutually balanced manner.

The invention includes the application of these features to both continuous and discontinuous control systems. In the continuous control type of system, the wayside inductors which receive the energy from and return it to the train, extend along the wayside more or less coincident with the block sections. The track rails themselves are preferably utilized as the wayside inductors. In the discontinuous control type of system the wayside inductor elements are localized coils. An object of the invention will therefore be appreciated to be that of providing an inductive type of system employing an inert wayside circuit and one capable of being employed for either intermittent or continuous train control. Further objects, such as those of obtaining more than two signal in-

dications and of providing a system which operates in accordance with the closed circuit principle, will be evident from the illustrative embodiments shown in the accompanying drawings in which:

Figures 1 and 2 show the application of the invention in an intermittent control type of system, Figure 1 being the train-carried portion, and Figure 2 a schematic showing of the wayside portion of the system.

Figure 3 shows the application of my invention to a continuous control type of system, the wayside system being shown in a simplified form.

Figure 4 shows a wayside system similar to that shown in Figure 3, superimposed upon ordinary block signal track circuits.

Referring to Figure 1, alternating-current energy is generated aboard the train by generator 1. The energy is passed through transformer 2, through conductors 3, 4, and 5, 6 to the train inductor coils 7 and 8. These coils may be tuned individually to the frequency of the generator by means of condensers 9 and 10. Each of the coils 7 and 8 embraces an inverted U-shaped laminated iron core and is so mounted on the train as to pass over and coact inductively with complementary coils disposed in the wayside.

The wayside coils, designated 11 and 12, in Figure 2, are likewise provided with U-shaped laminated iron cores. The wayside cores are made of large size because they are intended in themselves, without their coils, to affect the train-carried circuit, as will be described. When the train passes the wayside control point, train-coil 7 links magnetically with wayside-coil 11, and train-coil 8 with wayside-coil 12. The wayside coils may be tuned individually by condensers 13 and 14. The wayside coils are connected together in the manner indicated and their circuit is extended by means of conductors 15, 16 through the contacts of relays 17, 18 to transformer 19.

The two train coils and the two wayside coils are so connected in their respective circuits that current from generator 1 flowing through coils 7 and 8 induces current in coils 11 and 12 which are connected in series aiding relation with respect to each other in circuit 15, 16. This current flows through conductors 15 and 16 and through the primary winding *a* (which is center-tapped) of transformer 19. The current so established induces an E. M. F. in the secondary winding of transformer 19. Said secondary winding *b* sends current through a circuit which may be traced as follows, the relative polarity 55

being that which obtains at some one instant: Conductor 20 to the center tap of the primary *a* of transformer 19, through the two halves of the transformer winding in mutually parallel 5 opposing relation, thence in parallel along conductors 15 and 16, through coils 11 and 12, mutually in parallel, and back on conductor 21 to secondary winding *b*.

Thus the wayside circuit receives an excitation in one sense, as through the two coils 11, 12 10 connected in series and poled to be aiding around the circuit 15, 16, and transmits current 15 back in another sense through the two sides, 15 and 16, of the circuit in parallel connected by a 15 third conductor 21. The wayside inductor coils are thus energized in a mutually parallel and opposite sense for retransmission back to the train. The return-transmission wayside circuit, (traced by 20, 15 and 16 in parallel, 11 and 12 20 in parallel, 21 and secondary *b*), is therefore balanced and non-interfering with respect to the wayside power-supply circuit previously traced around conductors 15, 16, with inductors 11 and 12 in series. By virtue of the well known principle 25 of superposition, the wayside inductors 11 and 12 may be regarded as excited by the return current quite independently of the initial exciting current present in them. The wayside coils, thus reexcited, induce currents in the 30 train-coils 7 and 8. The E. M. F.'s set up in these coils are mutually opposing, and therefore neutralize, with respect to the original current supply circuit 5-6. They are however 35 mutually aiding with respect to and cause current to flow in a circuit superposed upon and balanced with respect to circuit 5, 6, the flow being at some one instant as follows: Along conductors 5, 6 in parallel; 3, 4 in parallel to the secondary of the current supply transformer 2; through the two halves of this winding in parallel opposing relation to the center tap and thence along conductor 22; through winding 23' 40 of the receiving relay 23, and back on conductor 24 to the point midway between coils 7 and 8. 45 By passing the received current through the train inductor coils in this balanced manner, it is impressed upon the actuating winding of the receiving relay to the exclusion of the outgoing current. The receiving relay is illustrated to 50 be of the A. C. excited type, current from the generator being supplied to the magnetizing windings through conductors 25, 26.

With respect to the use of the two pairs of 55 inductors simultaneously for the establishment of two distinct transmission paths, one for transmitting the exciting current to the wayside signal location and the other for selectively transmitting the signal indicating currents back to the train, the following further elucidation 60 may be useful: The train-carried inductors 7, 8 operate in series in circuit 5, 6 to deliver power to wayside inductors 11, 12. The latter in turn operate in series to transmit the power over circuit 15, 16, to the primary *a* of transformer 19. The return transmission path may be regarded 65 as originating in secondary winding *b*, and extends along 20, along 15, 16 taken in parallel, through wayside inductors 11, 12 taken in parallel, along 21 back to the secondary *b*. Thus the 70 wayside inductors operate in parallel for the return transmission to induce currents in train inductors 7 and 8 which flow correspondingly in parallel along conductors 5, 6, along 3, 4, traverse conductor 22, relay winding 23 and thence over conductor 24 back to the inductors. Thus the 75

two train-carried circuits, the power supply and the signal receiving are mutually balanced and non-interfering, and by including the two train-carried inductors in the balanced arrangement they both are rendered effective as simultaneous transmitters and receivers. This is also the case with the wayside inductors.

The system which has thus far been described constitutes two superimposed transmission paths, one functioning to supply energy to the wayside circuit, where the signal indications are impressed, and the other functioning to selectively transmit back to the train the energy carrying the signal indications. The way in which the signal indications are actually impressed upon and taken from the return transmission path will now be described.

The basis of signaling which is preferred for this discontinuous type of system is one wherein the wayside control elements are made to tend 20 normally to give a "stop" indication, and wherein the giving of a "caution" or a "clear" indication is accomplished by overcoming the "stop" indication and substituting for it the safer indication. Accordingly, there is provided in the present invention a tripping means which gives 25 a "stop" indication unless positively displaced by a "caution" or "clear" indication. The tripping means comprises a balanced circuit centered about the 3-winding balancing transformer, illustrated as included within the dotted rectangle 30. The 3-winding balancing transformer is of the type commonly known in telephone engineering as a hybrid coil and need not be described in detail. The circuit includes on one 30 side of the balance both of the train-coils 7 and 8 taken in series and aiding in their effects and on the other side a balancing coil or coils 27, 28. In cases where condensers 9, 10 are employed, balancing condenser 29 is included on 40 the balancing side. The inductance of coils 27-28 is made equal to the combined series connected inductance of coils 7 and 8 when over the cores of wayside coils 11 and 13, with the circuit 15-16 open.

Under this condition the circuit is balanced so that no current is induced in the middle winding of the hybrid coil, the electromotive forces induced in this winding from the two halves of the primary winding being equal and opposed. When the circuit is unbalanced these forces are unequal and a resultant current flows in a relay 31 connected in circuit with the middle winding of the hybrid coil.

With the wayside circuit open, as is the case 55 for the stop condition, the circuit for including current in the circuit of relay 31 tends to become balanced as the train coils pass over the wayside inductor cores. As a result, the current in relay 31 is greatly reduced and the relay contacts open. The train signal circuits are arranged so that this gives a stop indication. A stop indication will then also be given in case of failure of the source of current 1. When the train is between control points the circuit 60 is unbalanced and relay 31 is held closed by current transmitted from the generator 1 through the balancing transformer indicated by the rectangle 30.

Thus it will be seen that one indication, the 70 stop indication, is passed to the train merely by the action of the cores of wayside coils 11 and 12 in unbalancing a train-carried circuit. In actual operation this action comes into play upon the opening of circuit 15-16 by the re- 75

lease of relay 17. Relays 17 and 18 will be understood to be operated from the track circuit of the usual type of block signal system.

The safety indication is given when the wayside circuit is in the condition illustrated in Figure 2. The circuit is so arranged that when the train passes over the wayside control point the relative instantaneous polarity of the energy transmitted back to the train, and which enters winding 23' of the receiving relay, will be such as to move the armature of the receiving relay to, say, the left contact. This causes the actuation of relay 32 which in turn is made to display a clear indication through the appropriate local circuit arrangements. These arrangements form no part of the present invention and therefore are not shown.

The exhibiting of the intermediate or "caution" indication is accomplished as follows: Relay 17 is closed, relay 18 is opened. This reverses the relative instantaneous polarity of the energy fed back to winding 23 of the train-carried relay and the armature of the receiving relay is actuated to the right. Relay 33 becomes energized and functions to give the caution signal. It will be understood that the signal indications described above may be employed in conjunction with well known types of speed control devices to control automatically the speed of the train.

The wayside signaling relay contacts are illustrated connected in the wayside circuit at a point which is common to both of the two superimposed transmission circuits, one receiving from the train and the other transmitting to the train. They could as well be placed in the circuit at 20, 21, where they would be confined to the path transmitting to the train, and the transformer 19 would receive power from the train irrespective of the wayside relays.

It is desirable to note also that wayside transformer 19, constitutes a means for terminating the power-supply transmission channel and for turning it back upon itself over a superimposed balanced channel transmitting back to the train. By thus acting to interconnect two channels which otherwise are balanced one against the other, the transformer is really a means for effecting a total unbalance between the two channels in question, and in turn an unbalance between the transmitting and the receiving circuits upon the train. The unbalancing action is thrown in or out by relay 17, and the relative sense or polarity of the unbalance is controlled by relay 18. This constitutes another way of looking upon the modus operandi of the present type of system, including the continuous as well as the intermittent control system.

Referring now to the continuous control system of Figure 3; alternating-current energy from generator 1 is transmitted through transformer 2, along conductors 3, 4 and 5, 6 to the train-carried inductors 7, 8. These coils are disposed on the train in proximity to the track rails 11, 12 for the purpose of inducing current therein. The coils are preferably provided with laminated iron cores not shown. They may be tuned to the generator frequency by a condenser 9. The polarity of the coils is made such as to induce a current flow in the same direction in the two rails, as indicated by the solid line arrows. This current flows longitudinally along the rails to the end of the block section, and returns over a third conductor 21 provided along the right-of-way, as by being carried on the wayside pole

line. The transmission path may be traced as follows: along rails 11, 12 in parallel; along conductors 15, 16 in parallel; through the two halves of the winding of transformer 19 non-inductively to the center tap; along conductor 20; through a path which includes the wayside relay contacts and the winding of transformer 19, (which becomes the primary winding); back along the conductor 21 to the other end of the block; non-inductively through the center-tapped coil 19'; and thence back to the two rails. This circuit constitutes a closed circuit loop which receives energy inductively from the passing train.

The energy thus received, after being controlled in accordance with signal indications in a manner to be described subsequently, is retransmitted to the train in the following manner; current flowing in the loop circuit just described induces an E. M. F. in the secondary 20 (center-tapped) winding of transformer 19. This causes current to flow transversely between the track rails over a path which starts in conductors 15, 16 and includes the rails 11, 12 and is completed through the wheels and axles of 25 the train. In this way the track rails serve as a return-transmitting circuit as well as a non-interfering energy pick-up circuit. In the form described the two rails in parallel form the wayside energy pick-up circuit while in series they 30 function as the return-transmitting circuit. It will be understood that conditions could be reversed, i. e., the usual transverse rail circuit could be utilized for transferring the energy to the wayside and the superimposed longitudinal 35 rail circuit for the return transmission.

Referring now to the way in which the returned energy is received on the train: The current of the wayside return-transmission induces E. M. F.'s in the train pick-up coils 7' and 40 8', the polarity of which E. M. F.'s are such as to be mutually aiding with respect to circuit 22, 24 and to send current into winding 23' of the receiving relay. An amplifier A, preferably of the vacuum-tube type, may be inserted in the 45 circuit 22, 24 to increase the power available for operating the receiving relay. The circuit of the pick-up coils may be tuned by a condenser 9'. The receiving relay is preferably of the induction type, supplied with exciting current from 50 the generator 1 over conductors 25, 26.

The system thus far described constitutes an electric wave transmission path which extends from the train to the wayside point of signal control and then back again to the train. Both 55 the outgoing and the return paths are metallic circuits, and the looped transmission path so formed is to be distinguished from a circuit composed of a single wire looped out and back. This looped path is established continuously during the occupancy of a block by the train, and the return transmission is continuously available for the transmitting of signal indications to the train. The signal indications are transmitted as follows:

1. In accordance with the closed circuit principle of operation, the normal return transmission accomplishes by its receipt on the train the "clear" or "proceed" indication. The train relay is assumed to be thrown to the left, as 70 shown, for this condition.

2. For the transmitting of the "caution" indication relay 18 is assumed to be released by the wayside block signal system. The effect of this is to reverse the relative instantaneous 75

polarity of the current supplied to the rails from transformer 19, and in turn to reverse the current in train relay coil 23'. The relay armature is then swung to the right; and the caution indication is displayed in the locomotive cab and speed restriction is applied in a manner now well known in the art.

3. For the danger or "stop" condition, relay 17 is assumed to be released by the block signal system. This opens the energy supply circuit, cuts off the current from the rail inductors and in turn from winding 23' of the train receiving relay. The receiving relay therefore releases, opens the local train circuits, resulting in the display of the danger indication in the locomotive cab and in the application of a stringent speed limitation or a stop in accordance with practice well known in the art.

The wayside transmission paths of Figure 3 may be superimposed upon the ordinary block signal track circuits, as illustrated in Figure 4. The track circuits are here assumed to be of the direct-current-type. The superposition principle would be the same, however, were they of the alternating-current type. In the latter case the alternating-current provided on the train would be chosen to be sufficiently different in frequency from the alternating-current of the block system to permit of separating the two sets of currents by frequency-selecting means.

Referring now to Figure 4, the several block sections are designated 1, 2, 3, 4. The direct current for block 2, for example, is supplied by battery B_2 . The current flows through the following path: the contacts of relay R_1 , through one set of windings of transformer T_2 , to the rails AA; and along the rails to relay R_2 . The track relays are of the polarized type, having two sets of contacts, those designated by the letter N being the contacts controlled by the neutral winding and those designated by the letter P being the contacts which are controlled by a change in the polarity of the current. When the current is interrupted, the N contact arms release but the P contact arms hold. When the current is reversed, the N contact arms hold but the P contact arms reverse. Thus, the regular block-signal direct-current circuit portion of Figure 4 will be understood to operate as follows: A train occupying block 4 causes the N_2 contact arms of relay R_1 to release. This reverses battery B_2 of block 2 which in turn reverses the P_3 contact arms of relay R_2 . Battery B_3 is applied to block 3 in a normal manner and as a result relay R_3 holds both sets of contact arms N_4 and P_4 in the normal clear condition. These operations are illustrative of the ordinary block signal and are not novel.

The portion of the wayside system which is new and a part of the present invention, as described in connection with Figure 3, is shown as superimposed upon the ordinary block circuit and may be traced in block 2 of Figure 4 as follows: The energy supply circuit is from the train into rails AA in parallel, through the two line windings of transformer T_2 in parallel mutually opposing relation, along two of the N_2 contact arms in parallel, to B_2 . Were the N_2 contact arms drawn up by the actuation of relay R_1 , the circuit would continue through one contact arm of P_2 , through the winding (actually the primary winding), of transformer T_2 , back through the other contact arm of P_2 and back to the other end of the block over con-

ductor K; through a center tap of the winding of relay R_2 , without affecting the normal D. C. operation thereof, and thence back to the two rails in parallel. Return conductor K will be seen to correspond to conductor 21 of Figure 3; likewise transformer T_2 corresponds to transformer 19 of Figure 3.

When current is induced by a passing train in the longitudinal wayside pick-up circuit AA, K, the current tends to be passed back to the train over a transverse circuit, formed of the rails in series; as follows: The two secondary coils of transformer T_2 have series aiding E. M. F.'s induced in them as the result of current flow in the primary circuit just delineated. The secondary E. M. F.'s tend to set up current flow around a circuit 15, 16 which is closed upon itself at one end by the contacts of N_2 and battery circuit B_2 , which includes the two rails AA in series in the circuit, and which at the rail end is closed by the short-circuiting effect of the train upon the rails.

The ordinary D. C. track circuits of Figure 4 illustrate the three signal indications, stop, caution, and clear, to be set up for blocks 2, 3 and 4 respectively. In block 2 the stop indication is passed to the train simply by opening at N_2 the circuit which picks up the energy from the train. The train-generated energy is not returned to the train and, therefore, the receiving relay on the train is released. In block 3 the caution signal is transferred to the train by virtue of the relative reversal at P_3 of the current which is fed back to the train. This results in a reversal of the train-carried relay in the manner previously explained. In block 4 the clear or proceed signal condition is transferred to the train because the circuit is in such condition as to send energy back to the train in relatively normal phase relation. Thus a train in passing along from block 4 to 3 to 2 will meet successively, and be subjected to control in accordance with, the clear, caution and stop indications.

Referring to the train-carried arrangement disclosed in Figure 3 it will be noted that a separate set of sending and receiving coils is employed. Actually one pair of coils could be used as is done in the arrangement of Figure 1. The separate coil arrangement has the advantage of improving the balance separation obtained between the superposed longitudinal and transverse circuits. In other words, the train receiving circuit is subject to less direct influence from the transmitting circuit because of the transmission loss which intervenes between the sending and receiving coils by virtue of their separation and by virtue of their being placed on opposite sides (front and rear) of one or more trucks of the locomotive.

Having now described the invention, what I claim is:

1. A wayside circuit for train control purposes comprising two inductors, means for connecting the two inductors in parallel with each other in the circuit for transmission in one direction, from or to the train, and in series with each other in the circuit for transmission in the reverse direction, means in the wayside for interconnecting the two superimposed paths thus formed, together with means on the train whereby energy is received from said wayside circuit to the substantial exclusion of the energy which is transmitted into it.

2. In a train control system, a train-carried alternating current supply, a train-carried inductor unit including a combination of transmitting and receiving inductor coils, said coils being capable of being balanced in respect to the direct effect of said source, together with an inert wayside circuit provided with a pair of inductors for receiving power from the train-carried source and for selectively influencing the train-carried receiver in accordance with traffic conditions ahead.

3. In a train-control system, a train-carried inductor winding with a coacting wayside inductor forming one inductive coupling, a second train-carried inductor winding with a coacting wayside inductor forming a second inductive coupling, a connecting circuit on the train which combines the inductive effects of said two train-carried windings in series with each other in the circuit for transmission of signaling current in one direction between the train and the wayside, and in parallel with each other in the circuit for transmission in the reverse direction.

4. In a train-control system, a train-carried source of alternating current, a pair of train-carried inductor coils supplied with alternating current from said circuit, a train-carried signal receiving circuit utilizing the same pair of inductor coils, and means for so connecting the receiving circuit and said source to the inductor coils as to prevent the alternating supply current from directly affecting the receiving circuit; together with a wayside circuit comprising two inductors and means for connecting them in parallel with each other in the circuit for transmission of signaling current in one direction, from or to the train, and for connecting them in series with each other in the circuit for transmission in the reverse direction.

5. In a system for transmitting signals between a train and the wayside; a two-wire circuit for transmitting in one direction between the vehicle and wayside, a circuit derived in

part therefrom for transmitting in the reverse direction, comprising a third wire connected to the midpoint of the two-wire circuit at each end and completed by the conductors of the two-wire circuit working in parallel, a transformer in the wayside, including primary and secondary windings, and means in one winding thereof to make said midpoint connection, one of said windings being included in said two-wire circuit and the other being included in the third wire of the derived circuit.

6. In a train signaling system, the trackside arrangement which includes a two-wire circuit for transmitting signal current in one direction between train and trackside, a circuit derived in part therefrom for transmitting signal current in the reverse direction comprising a third wire connected at each end to a midpoint of the two-wire circuit and completed by the conductors of the two-wire circuit working in parallel, said circuits including a transformer having primary and secondary inductive elements, one of said elements being divided into two equal coils which are connected in series with each other in the two-wire circuit, thereby forming one of the midpoints, and the other of said inductive elements being included in said third wire.

7. In a train-control system, a train-carried source of alternating current, a pair of train-carried inductor coils supplied with alternating current from said source, a train-carried signal receiving circuit utilizing the same pair of inductor coils, and means for so connecting the receiving circuit and said source to the inductor coils as to prevent the alternating supply current from directly affecting the receiving circuit; together with a wayside circuit comprising two inductors and means including a transformer for connecting them in parallel with each other in the circuit for transmission of signaling current in one direction, from or to the train, and for connecting them in series with each other in the circuit for transmission in the reverse direction.

LLOYD ESPENSCHIED.
